UNITED STATES PATENT OFFICE.

IDA M. JENKINS, OF PRINEVILLE, OREGON.

DESIGN FOR A BROOM ATTACHMENT.

50,308.

Specification for Design.

Patented Feb. 13, 1917.

Application filed October 6, 1916. Serial No. 124,195. Term of patent 14 years.

To all whom it may concern:

Be it known that I, IDA M. JENKINS, a citizen of the United States, residing at Prineville, in the county of Crook and State of Oregon, have invented a new, original, and ornamental Design for Broom Attachments, of which the following is a specification, reference being had to the accompanying drawing, forming a part thereof.

The figure is a perspective view of a broom attachment, showing my new design.

I claim:

The ornamental design for a broom attachment, as shown.

IDA M. JENKINS.

Witnesses:

L. M. BECHTELL,
WILLARD H. WIRTZ.
